UNITED STATES PATENT OFFICE.

CHAS. A. POSTLEY, OF SPRING GARDEN, PENNSYLVANIA.

SELF-ACTING GUARD-FROG.

Specification of Letters Patent No. 8,171, dated June 24, 1851.

To all whom it may concern:

Be it known that I, CHARLES A. POSTLEY, of the district of Spring Garden, in the county of Philadelphia and State of Pennsylvania, have invented a new and Improved Self-Acting Lever or Shifting Guard-Frog which Performs All the Duties of a Switch Without the Loose Rail; and I do hereby declare that the following is a full, clear, and exact description of the construction and operation of the same, reference being had to the annexed drawings, making a part of this specification, in which—

15 Figure 1, is a plan of the rail and frogs; Fig. 2, a longitudinal section showing the arrangement of the levers, &c.; Fig. 3, a plan of the working part, the rails being removed; Fig. 4, a transverse section, and 20 Fig. 5, a view in elevation, of the guard and lifting levers and vertical catch detached.

The same letters referring to the same parts a particular reference to the figures 25 is deemed unnecessary.

Letter *a*, surface of the ground; *b*, *b*, the rails; *d*, *d*, steel points to rails; *e*, *e*, are levers acting upon the guards *f'*, *f''*, and upon the upright bars or rods, 3, 3; *f'*, *f''* 30 guards; *g*, *g*, *g*, *g*, iron castings forming a chamber for levers *e*, *e*, and *h'*, *h''* to work in; *h'*, *h''*, are also levers, acting upon the upright arms or bars 1, 1, and 2, 2, of levers *i*, *i*, and *k*; *i*, *i*, lifting levers; *k*, *k* catch levers; 35 *l*, *l*, are also catch levers; Figs. 1, 1, 2, 2 and 3, 3 in the various drawings are upright bars or rods; *m*, *m*, are upright levers acting directly upon and being attached to the catches *n*, *n*, by means of the connecting rods 40 *t*, *t*; *n*, *n*, vertical catches; *o*, *o*, weight acting upon the vertical catches *n*, *n*, by arm or rod *p*; *q*, catch in the guard; *r*, *r*, guard lever bars or oscillating frame; *s*, vault for the levers to work in.

45 The nature of my invention consists in placing, 2 levers *h'*, *h''*, inside the track, and at such a distance from the rails, that the flanges of the wheels of the engine and cars shall pass freely along the road without 50 touching them; one end of said levers being raised higher than the rails while the other is depressed, both sets of levers working upon the upright arms of levers *k*, *k*, as fulcrums, these levers are acted upon by shifting cams or wheels attached to the locomotive. There are also two other levers *e*, *e*,

working close up to the rails and acted upon by the flanges of the wheels of the engine; said levers acting upon the guards *f'*, *f''*, and the upright arms or bars 3, 3, as herein-after described. The levers *h'*, *h''* act upon the upright arms or rod 2, near one end as shown in Fig. 2, the arms 2, serving as a fulcrum. The levers *e*, *e*, have for their fulcrum the upright arms or rod 3, near the center as shown in Fig. 2, the upright arms 1, 1, 2, 2, 3, 3, are made of iron, working on pivots at the ends of the levers *i*, *k*, and *l*, and so placed as to be acted upon in succession by the shifting cams passing over the levers *h'*, *h''*, and the flanges of the wheels passing over the levers *e*, *e*, their use being to discharge or free the catch and shift the guards, by acting upon the levers *i*, *k*, *l*, and *m*. The levers *i*, *k*, and *l*, can be made of any suitable wood; levers *k*, are placed in such a manner, and so connected that they shall act upon opposite sides, to that upon which they are acted; they discharge or free the vertical catch *n*, *n*, previous to the lifting levers *i*, *i*, being acted upon by the upright arms 1, 1. The levers *i*, *i*, are connected with the guard *f*, for the purpose of raising it after the catch has been discharged from the opposite side; they are 80 acted upon by the levers *h'*, *h''*, by means of the upright arms 1, 1. The lever *l*, is worked by the engine wheel flange passing over the lever *e*. Its use is to discharge the catch previous to the lever *e*, acting upon the guard *f'*. The weights *o*, are necessary to draw the catches *n*, *n*, into their places after the guards are raised; they act on the catches *n*, by means of the arms *p*, upon which they are placed, all the levers excepting *e*, *e*, and *h'* and *h''* work in a pit or chamber of good substantial mason work.

85 The operation of my invention is as follows: Shifting cams or wheels being placed upon the locomotive in such a manner that they can be worked by the engineer as occasion may require by bringing them in contact with either of the elevated levers *h'* or *h''*, the cam or wheel acting upon but one of the levers at a time. At the moment the cam or wheel bears upon the lever *h'*, the lever *h'*, is depressed, acting upon its fulcrum the upright arm 2, causing one end of the lever *k*, to descend, while the other end is raised, thus throwing out the catch by 90 means of the upright lever *m*, and raising the guard *f'* and lowering the guard *f''*.

In further explanation of the operation, should the cam or wheel act upon the lever h^2 the catch will be freed from the guard f' .

As the engine passes on the lever h^2 is still further depressed causing it to act upon the upright arm or bar 1, lowering one end of the lever i , forcing up the guard f^2 , and lowering the guard f' .

The levers e, e , are worked by the flanges 10 of the wheels of the engine coming in contact with them, and causing them to sink, by which they are made to act upon the upright arms 3, (which also serves as a fulcrum to the lever e ,) thus causing the 15 catch to be freed and the guard to sink, at the same time the guard and lever on the

opposite side are raised, the upright catches n , are connected with and acted upon by the upright levers m .

What I claim as my invention and wish to 20 secure by Letters Patent, is—

The combination of the rising and falling guards $f' f^2$ with the levers e, e , and $h' h^2$, by means of an arrangement of levers, connecting rods, etc, substantially such as herein 25 specified, and acting in the manner and to produce the results herein set forth.

CHARLES A. POSTLEY.
